UNITED STATES PATENT OFFICE.

JULIUS KAYSER, OF NEW YORK, N. Y.

DESIGN FOR A GLOVE.

SPECIFICATION forming part of Design No. 21,918, dated October 25, 1892.

Application filed July 27, 1892. Serial No. 441,419. Term of patent 7 years.

To all whom it may concern:

Be it known that I, JULIUS KAYSER, of the city, county, and State of New York, have invented a new and original Design for Gloves, 5 of which the following is a specification, reference being had to the accompanying drawing.

The drawing is a back view of a glove embodying my design.

10 The leading feature of my design consists in a glove provided with a representation of a series of butterflies wrought into or placed upon the surface of the wrist and arm portion thereof.

Referring by letter to the drawing, A designates a glove, and A' shows the figures, consisting of the body portion *a* and the wings *a'*, extended therefrom.

What I claim is—

The design for a glove, substantially as 20 herein shown and described.

In testimony whereof I have signed my name to this specification in the presence of two subscribing witnesses.

JULIUS KAYSER.
